UNITED STATES PATENT OFFICE.

WILLIAM E. TAYLOR, OF EAST ORANGE, NEW JERSEY, ASSIGNOR TO AMERICAN CAN COMPANY, OF NEW YORK, N. Y., A CORPORATION OF NEW JERSEY.

CAN-LABELING.

1,229,187.

Specification of Letters Patent. Patented June 5, 1917.

Application filed June 2, 1913. Serial No. 771,156.

To all whom it may concern:

Be it known that I, WILLIAM E. TAYLOR, a citizen of the United States, residing in East Orange, in the county of Essex and 5 State of New Jersey, have invented a new and useful Improvement in Can-Labeling, of which the following is a specification.

This invention relates to an improvement in can labeling and the invention consists in 10 providing sheet metal food preserving and other cans with a sheet metal label of a construction and method of attachment more particularly hereinafter set forth and made the subject matter of claims.

15 In the accompanying drawing, Figure 1 is a top or plan view of a sheet metal sardine can embodying this invention; Fig. 2 is a longitudinal, vertical section of the same taken on the line 2—2 of Fig. 1; Fig. 3 is a 20 vertical cross section of the same taken on the line 3—3 of Fig. 1.

In the said drawing, A is the body of the can, and which may be provided with the usual removable bottom B adapted to be 25 moved when opening the can by means of a rolling key. C is the key for opening the can placed in a recess D formed in the head of the can. E is the head of the can secured to the walls of the body by seam F. This 30 cover is so constructed and secured to the can body as to present an upward extension or rim, the entire head or cover excepting the seaming part of the same, being thus countersunk below the upper edge of the can 35 wall, producing a shallow cavity to receive and retain the sheet metal label. G is the sheet metal label made to conform in outline to the general shape of this cavity and consisting of a sheet of metal cut to this 40 shape and having lithographed or printed upon one of its surfaces the matter desired upon the label. This sheet metal label is applied to the filled and closed can by being placed flatwise in the cavity at the top of 45 the can and secured to the can by the bend-

ing in of the seaming wall at two or more points, as indicated at H, H. Before the label is applied and secured in place the key for opening the can may be placed in its recess, as indicated in the drawing, and the 50 label will thus serve to retain the key in place during shipment. To get at the key the label may be removed from the can by simply springing it out of its engagement with the walls of the seam. The label being 55 a simple flat sheet of tin with the printing upon it, may be retained by the consumer to serve as a manufacturer's card, the can and the key being thrown away.

I claim:—

1. The combination with a can having a countersunk head, and an upstanding bendable seam around said head by which seam the can body and said head are united, of a resilient sheet metal label plate independent 60 of said head and conforming to the countersunk portion thereof, and removably held in place by opposite sides of the said upstanding seam which are bent toward each other over the edges of the label plate, the edges 65 of said plate being resiliently braced outward against the base of said seam.

2. The combination with a key-opening can having a countersunk head, and an upstanding bendable seam around said head by 70 which seam the can body and said head are united, of a resilient sheet metal label plate independent of said head, removably held in place by opposite sides of the said upstanding seam which are bent toward each other 75 over the edges of the label plate, the edges of said plate being resiliently braced outward against the base of said seam; the head being formed with a depressed recess, and a removable can-opening key held in said 80 recess under the label plate.

WILLIAM E. TAYLOR.
